UNITED STATES PATENT OFFICE

121,583

DESIGN FOR A DICTATING MACHINE CABINET

Gustav F. Braun, Elizabeth, N. J., assignor to
Thomas A. Edison, Incorporated, West Orange,
N. J., a corporation of New Jersey

Application November 13, 1939, Serial No. 88,237

Term of patent 7 years

To all whom it may concern:

Be it known that I, Gustav F. Braun, a citizen of the United States, residing at Elizabeth, in the county of Union and State of New Jersey, have invented a new, original, and ornamental Design for a Dictating Machine Cabinet, of which the following is a specification, reference being had to the accompanying drawing, forming a part thereof.

In the drawing:

The single figure is a perspective view of a dictating machine cabinet showing my new design.

Referring to the drawing, the left and right hand sides of the cabinet are identical in form and appearance; and the rear side of the cabinet has a plane vertical surface except at its upper end portion which curves forwardly as indicated and except for the two pairs of spaced horizontal bands which extend entirely around the top and bottom portions of the cabinet.

I claim:

The ornamental design for a dictating machine cabinet, as shown and described.

GUSTAV F. BRAUN.
